UNITED STATES PATENT OFFICE.

FREDERICK A. BALLOU, OF NAYATT, AND ROGERS T. STAFFORD, OF EAST PROVIDENCE, RHODE ISLAND, ASSIGNORS TO B. A. BALLOU & CO., INC., OF PROVIDENCE, RHODE ISLAND, A CORPORATION OF RHODE ISLAND.

DESIGN FOR A SHOE STRAP.

Application filed May 7, 1927. Serial No. 21,884. Term of patent 14 years.

To all whom it may concern:

Be it known that we, FREDERICK A. BALLOU, a citizen of the United States of America, residing in Nayatt, county of Bristol, State of Rhode Island, and ROGERS T. STAFFORD, a citizen of the United States of America, residing in East Providence, county of Providence, State of Rhode Island, have invented a new, original, and ornamental Design for a Shoe Strap, of which the following is a specification, reference being had to the accompanying drawing, forming a part thereof.

The design consists essentially of an orna-

mental shoe strap unit having ornamental attaching members at its ends, the strap being adapted to extend from opposite edges of the shoe over the instep of the wearer.

Figure 1 is a front view of the shoe strap in extended position and Figure 2 is an edge view of the shoe strap, showing our new design.

We claim:

The ornamental design for a shoe strap, substantially as shown and described.

FREDERICK A. BALLOU.
ROGERS T. STAFFORD.
